MATERIAL MIXING DEVICE

Joseph A. Lynch, Middletown, N. Y.

Application January 15, 1941, Serial No. 374,588

1 Claim. (Cl. 259—101)

This invention relates to a material mixing device and more particularly to a means for mixing coloring matter in oleomargarine, and it consists in the constructions, arrangements and combinations herein described and claimed.

It is a particular object of the invention to provide a mixing device of extreme simplicity in construction, as well as in operation, and in which the coloring matter and oleomargarine will be homogeneously mixed with a minimum of effort.

It is also an object of the invention to provide a mixing device in which the mixing chamber is provided with a stop means cooperable with an oscillatable mixing paddle or piston to insure complete mixing of the coloring matter and the oleomargarine.

It is a still further object of the invention to provide a device of the kind stated which is of a portable nature and which may be readily dismantled for cleaning and refilling.

Additional objects, advantages and features of invention will be apparent from the following description and accompanying drawing, wherein

Figure 1 is a top plan view of the device, with a portion broken away.

Figure 2 is a side elevation thereof.

Figure 3 is a cross section on the line 3—3 of Figure 1.

Figure 4 is a perspective view of the mixing paddle or piston.

Attention is first invited to Figures 1, 2, and 3, wherein there is shown a substantially rectangular base 10 upon which there is suitably secured a housing 11 having a cylindrical chamber 12. A segment-shaped abutment 13 is formed on the wall of the chamber, the apex 14 of which is directed toward the axis of the chamber 12 but stopping short thereof to accommodate a shaft 15 of a planiform mixing paddle or piston 16. It should be noted that the apex 14 approaches the shaft 15 quite closely, in order that material being mixed may not pass therebetween during operation. The abutment 13 extends the full height of the chamber 12.

The paddle or piston 16 includes a lower bearing 17 adapted to be oscillatably mounted in an annular recess 18 formed axially of the base and an upper bearing 19 positioned within a circular opening 20 of a closure top 21, when the parts are in assembled relation. The upper end of the shaft 15 is of angular formation for rigid mounting of an operating handle 22, for oscillating the paddle or piston.

A compression plate 23 is integrally formed with the shaft 15 extending at right angles thereto, of a height corresponding to the height of the chamber 12, and of a length so as to abut the peripheral wall of the chamber.

The plate 23 is formed with right angular slots

24, four being shown, arranged in pairs, the corner of each pair of slots being positioned on a line diagonal to each other. Thus, there is provided a horizontally disposed open portion 25 and a vertically disposed portion 26, and obviously when the paddle or piston is oscillated, the material whether it be oleomargarine or otherwise, will be forcibly compressed and pass through the openings to effect a thorough mixing of the mass.

In the present instance, the closure top 21 is shown as a flat circular disk of a diameter corresponding to the outer circumference of the housing 11 and secured thereto by means of stud bolts 27 circumferentially spaced around the housing. Wing nuts 28 are employed upon the bolts to permit ready removal of the closure top.

Considerable pressure is required to mix a mass of material, and in order to firmly hold the device against movement, there are provided a pair of clamp bolts 29 comprising a right angular arm 30 and a shank 31 of a length to extend through the base 10. The outer end of the shank is threaded and receives a wing nut 32. The arm 30 is positioned beneath an edge of a table or the like 30', and by tightening of the nut 32 the arm will be drawn tightly against the table portion.

In order that an even and forcible pressure may be applied to the paddle or piston, the handle 22 is provided with a knob 33 at one end, while the opposite end of the handle is shaped to form a grip portion.

As clearly shown in Figure 1, the segment shaped abutment 13 receives the paddle or piston 16 flatly thereagainst, and obviously, the material in the chamber will be extruded through the slots 25 and 26, so that a very thorough intermix of the material is obtained.

While I have shown and specifically described my invention, this is by way of illustration only, and I consider as my own all such modifications in structure as fairly fall within the scope of the appended claim.

I claim:

In a device of the character described comprising a body member having an annular chamber, said chamber having an axial bearing, a shaft journaled in the bearing, a planiform piston carried by the shaft of a size to snugly traverse the walls of the chamber, said piston having a plurality of angular slots extended transversely therethrough, a removable closure for the chamber having an axial opening for the shaft, a segmental-shaped abutment fixed in the chamber, the apex of which stops short of the shaft, and having side walls complementary to the faces of the piston, and a double grip handle member fixed to the shaft.

JOSEPH A. LYNCH.
